(57) **CLAIM**

The ornamental design for a display screen with application icon, as shown and described.

DESCRIPTION

FIG. 1 is a front view of a display screen with application icon showing the new design enlarged and without the broken line disclosure for clarity of illustration; and, FIG. 2 is a front view of a display screen with the application icon shown in FIG. 1.

The irregular broken-line perimeter shown in FIG. 2 illustrate a display screen and forms no part of the claimed design. The remaining broken lines shown in FIG. 2 illustrate portions of a graphical user interface and form no part of the claimed design.

1 Claim, 2 Drawing Sheets
